UNITED STATES PATENT OFFICE.

EDWARD W. RYAN, OF YPSILANTI, MICHIGAN.

DESIGN FOR A COMMUNION-CUP FILLER.

SPECIFICATION forming part of Design No. 30,935, dated June 6, 1899.

Application filed June 30, 1898. Serial No. 684,885. Term of patent 7 years.

To all whom it may concern:

Be it known that I, EDWARD W. RYAN, a citizen of the United States, residing at Ypsilanti, county of Washtenaw, State of Michigan, have invented a certain new and useful Design for a Communion-Cup Filler; and I declare the following to be a full, clear, and exact description of the invention, such as will enable others skilled in the art to which it pertains to make and use the same, reference being had to the accompanying drawing, which forms a part of this specification.

This design relates to communion-cup fillers, of which the following is a specification, reference being had to the accompanying drawing.

The figure is a side elevation of a communion-cup filler, the design of which consists in a conical body A, having at the base oval beads $a a' a''$ and at the top b. At one side

is a half-oval handle B, above which and resting on which is a globular ball D, connecting with the conical body by a neck d. At the side opposite the handle B, starting near the base of the cone just at the bead a' , is a curved 25 tubular spout E. The angle or opening between the spout and the body of the cone is filled with an opaque plate e that extends about half-way up the cone and the corresponding distance up the tubular spout. 30

What I claim is—

The design for a communion-cup filler, shown and described.

In testimony whereof I sign this specification in the presence of two witnesses.

EDWARD W. RYAN.
